UNITED STATES PATENT OFFICE.

JOHN WOOLRIDGE, OF LIBERTYVILLE, ILLINOIS.

CULTIVATOR.

SPECIFICATION forming part of Letters Patent No. 295,607, dated March 25, 1884.

Application filed December 12, 1883. (No model.)

To all whom it may concern:

Be it known that I, JOHN WOOLRIDGE, residing at Libertyville, in the county of Lake and State of Illinois, and a citizen of the United States, have invented certain new and useful Improvements in Cultivators, of which the following is a full description, reference being had to the accompanying drawings, in which—

- 10 Figure 1 is a top or plan view with the tongue broken away; Fig. 2, a side elevation with a portion of the frame broken out and one of the wheels removed, and the tongue also broken off; Fig. 3, a cross-section through the frame 15 on line xx of Fig. 1; Fig. 4, a cross-section through one of the beam-supports; Fig. 5, a detail in longitudinal section of one of the beam-supports; Fig. 6, a top or plan view with the seat and wheels removed, showing the position of the beam - carrying devices when 20 swung or moved to have the shovels dodge uneven plants.

This invention relates to riding straddle-row cultivators, and has for its objects to improve the devices by which the plows or shovels are swung out of line for dodging uneven plants, to improve the means for raising the beams and regulating the depth of cultivation, and to improve generally the construction and operation of the machine; and its 25 nature consists in providing jointed or pivoted bars swinging laterally at the center for carrying the beams in or out, as required for the condition of the plants; in providing a 30 bracing and support for the pivoted bars, formed of a horizontal bar at the top, with vertical standards and diagonal bracing, as hereinafter more specifically described; in providing a sliding standard, to the lower end of 35 which the forward ends of the beams are connected, and having devices by which the standard can be raised or lowered to regulate the plowing depth; in providing a treadle operated by the foot for throwing the beams out of 40 operation, and in the several parts and combinations of parts hereinafter described, and 45 pointed out in the claims as new.

In the drawings, A represents a circular rim, made of wood or metal or partly of wood 50 and partly of metal, as may be desired. This rim is of sufficient circumference for the ordinary width of cultivators, and forms the frame for supporting the tongue, seat, and other appliances.

B represents brackets, secured in any suitable manner to the rim or frame A, and having at their lower ends a suitable spindle for the wheels, the brackets being located on each side of the rim or frame, and in line with each other.

C represents the wheels, which may be made in any suitable and well-known manner, and of sufficient diameter to carry the rim or frame A above the row of plants, so that the beams will straddle such rows.

D represents bars, pivoted at their front ends to the under face of the piece P' or frame A by suitable pins or bolts, *a*, and in such manner as to bring the pivotal points on each side an equal distance from the center of the frame, fore and aft.

E represents bars, pivoted at their rear ends, as shown, to the under face of a cross-bar by suitable pins or bolts, *c*, which pins or bolts pass through slots *d*, formed in the rear ends of the bars, the object being to allow lost motion in swinging the bars in and out. The bars D are each provided at their rear ends with an enlarged portion, *b*, in which is a circular opening, and the bars E are each 80 provided at their forward end with a corresponding portion, *e*.

F is a horizontal bar or cross-piece, having at each end an enlarged portion, *f*, with a circular opening.

G represents diagonal braces, one running from each bar D downwardly and rearwardly, and terminating in an enlarged portion, *g*, with a circular opening.

H represents diagonal braces, one running from each bar E downwardly and forward, and terminating in an enlarged portion, *h*, in which is a circular opening.

I represents diagonal braces running from the center of the bar F downwardly and on each side, and terminating in an enlarged portion, *i*, in which is a square or rectangular opening *j*.

J represents posts or standards, one for each side of the machine, and each having a central longitudinal opening coinciding with the opening *j* in the head *i*. The posts or stand-

ards J and the braces I may be cast or otherwise formed in one piece, or the posts and braces may be formed of independent pieces suitably secured together and to the cross-bar 5 F, and when the parts are together the posts or standards are to be secured in the heads f and i at the top and bottom; so as to be firm and secure, and constitute, with the cross-bar F and braces I, a rigid frame.

10 K represents shanks, one for each standard or post J, the shank passing up through the opening in the standard, and being somewhat longer than the length of the standard, so that its upper end will project above the top of the standard, while its lower end extends sufficiently below the bottom of the standard for the attachment of the plow-beam, and to allow of the required amount of vertical play to regulate the depth of cultivation. The 15 lower end of each shank K is provided with a head or enlarged portion, k, having a rearwardly-extending tooth or projection, k'.

15 L are cam-levers, one for each shank K, and secured to the top of the shank by a suitable pin or pivot, l. The acting portion L' of each lever is formed of two plates, l', having a curved bearing-edge, with a space between them for the passage of the upper end of the shank, and the bearing-edges are so arranged 20 in relation to the top of the bar F as to bear thereon and form a fulcrum, by which, as the handle L is raised or lowered, the shank K will be raised and lowered, raising and lowering the forward ends of the plow-beam.

25 M represents heads or beam-plates, one for each shank or standard, and each having ears m, between which the head k is located, to which head the beam-plate is secured by a suitable pin or bolt, n, passing through the 30 ears m and the head k, so as to allow of free vertical movement of the beams, and the beams are held in a straight line by the opening j, which corresponds in shape to the shape of shank, forming a lock against the turning of 45 the shank in the standard J.

35 M' represents the plow-beams, formed as shown, or in any other suitable and well-known manner, and carrying at the ends shovels or plows, as usual. The forward end of the beam 40 is secured to the head or plate M by suitable bolts, or otherwise.

45 N represents curved arms or levers, one located on the inside of each beam plate or head M, and secured in place by rivets, or in any other 50 suitable manner, and the upper end of each arm or lever is branched, forming a foot-rest, N', on which the foot of the operator can be placed, and through the curved arm or lever raise the rear end of the plow-beams, throwing 55 the plows up out of use.

60 O is a seat mounted on the cross-bar O', which bar is secured in any suitable manner to the rim or frame A at the rear end of the machine.

65 P is a tongue secured at its rear end to a cross-bar, P', located on and secured to the rim or

frame A at the front of the machine. The seat and tongue may be of the form shown, or of any other suitable and well-known form, and they can be attached to the frame or rim A in 70 some other manner than through the cross-bars O' P'. The spindle-brackets B are secured to the rim or frame by bolts or otherwise, and the bars D are pivotally secured at their front ends to the cross-bar P', or other 75 support on the frame, while the bars E are pivotally secured at their rear ends to the cross-bar O', or other support on the frame, so as to bring the inner or free ends of the two bars in line, one over the other, and, as shown, 80 when the inner ends are brought in line the end b of the bars D comes above the end e of the bar E, the end e being thrown down for this purpose, and the end h of the brace H for the bar E comes above the end g of the brace 85 G for the bar D, so that the two bars form a support vertically one for the other. The ends b, e, g, and h are brought in line, so that the openings in each will coincide, and the posts or standards J, with the braces I thereon, 90 are passed up through the openings in the heads b, e, g, and h on each side, bringing the end or head i of each brace in contact with the end or head g, as shown in Fig. 2. The bar F is then slipped onto the upper end of the 95 posts and secured to the posts by riveting or in some other suitable manner, and the braces I are bolted or otherwise secured to this cross-bar, uniting the bars D and E to the respective posts J in such manner as to form 100 a pivotal connection for the bars, by which they are free to swing sidewise, as shown in Fig. 6. The shanks K are passed up through 105 their respective posts J, and the levers L secured to their upper ends, so as to bear on the upper face of the cross-bar F. The beam-head M and beams, with the foot-treadle N N' secured thereto, are pivoted to the lower end of each standard, the tooth or projection k', when the parts are together, coming beneath the under side of the beam-plate, and forming a stop against the downward dropping of the beams at the rear end. The tongue and seat and the wheels are attached, when 110 the machine is ready for use.

115 In operation the machine is drawn forward by the team, in the usual manner of straddle-row cultivators, with the beams on each side of the row of plants, and when the row is straight the bars D E on each side are kept in line, 120 causing a straight line of travel for the beams; but when the row is crooked or some of the plants are out of line, so as to require dodging, the operator, by means of his foot, can throw the beams to either side by turning the 125 bars D E in the direction required, such turning being permitted by the pivotal connection of the free ends of the bars D E and their braces G H and the standards or posts J, and this sidewise swinging of the bars D and E is 130 provided for by the slots d in the rear ends of the bars E, which furnish the proper amount

of lost motion for this purpose. The depth of cultivation is regulated in the form of construction shown by the levers L L', by means of which the forward end of each beam can 5 be raised or lowered, as required, for the depth of cultivation, the levers when down permitting a deep cultivation, and when up a shallow cultivation.

A rack-and-pinion or a rack-and-cog segment or some other device could be used in 10 place of the cam-levers L L' to adjust the running depth.

When it is desired to throw the shovels up 15 out of use, the operator, with his feet, presses forward and down on the treadles N N', thereby throwing the rear ends of the beams up, raising the shovels out of the ground.

The frame, being formed of a circular rim, 20 is very simple in construction, and at the same time is strong, durable, and cheap, and it leaves a sufficient space for the location and operation of the other parts, and does away with the various forms of bracing heretofore required in the usual construction of cultivator-frames, which bracing adds to the cost of 25 the machine, and in some cases interferes with a free operation of the other parts. The parts D and E, having a free pivotal connection at their inner ends, allow of a free side 30 movement, and at the same time these bars, with their braces, furnish a strong support for the plow-beams, and being pivoted to the same standard or post which carries the pivotal connection for the plow-beam, the center 35 of motion and of vertical play are located at the same point, so that no binding of the parts and interference with the operation of side movement and vertical adjustment can take place. The bars D E, cross-bar F, braces G 40 H I, posts J, and sliding shanks K furnish a frame-work and support for the beams possessing the required rigidity and firmness to resist the draft in use, and at the same time allow of a perfect freedom of movement, by 45 which the dodging of the plants and the depth of plowing can be regulated without the adjusting of one interfering with the other.

The pivoted swinging bars, bracing, pivot standards or posts, and sliding shanks carrying the plow-beams can be used with other 50 forms of frames than the circular one shown.

What I claim as new, and desire to secure by Letters Patent, is—

1. The bars D E, pivotally connected at their inner ends to permit of side movement, 55 for changing the travel of the plow-beams, substantially as and for the purpose specified.

2. The bars D and bars E, having slots d in their rear ends, in combination with a post or standard carrying the plow-beams and forming a pivot for the inner end of the bars D E, 60 substantially as and for the purposes specified.

3. The bars D and E, in combination with the braces G and H, cross-bar F, and posts or standards J, substantially as and for the pur- 65 poses specified.

4. The bars D and E, in combination with the cross-bar F, posts or standards J, and braces G, H, and I, for forming a frame-work and support which permits of free side move- 70 ment, substantially as and for the purpose specified.

5. The bars D and E, cross-bar F, posts J, and suitable bracing, in combination with the sliding shanks K and the plow-beams, for ad- 75 justing the running depth of the plows and allowing of side movement, substantially as and for the purpose specified.

6. The posts J, forming a pivot for side movement, in combination with sliding shanks 80 K, for attaching the plow-beams and locating both movements at a common point, substantially as specified.

7. The bars D and E, cross-bar F, post J, and suitable bracing, in combination with 85 the sliding shanks K, plow-beams, and foot-treadle, substantially as and for the purposes specified.

JOHN WOOLRIDGE.
